UNITED STATES PATENT OFFICE

155,237

DESIGN FOR A COMBINED PLACE CARD AND FLOWER HOLDER

Edna L. Sanders, Laytonville, Calif.

Application January 17, 1947, Serial No. 136,196

Term of patent 3½ years

(Cl. D35—3)

To all whom it may concern:

Be it known that I, Edna L. Sanders, a citizen of the United States, residing at Laytonville, in the county of Mendocino and State of California, have invented a new, original, and ornamental Design for a Combined Place Card and Flower Holder, of which the following is a specification, reference being had to the accompanying drawing, forming a part thereof.

Figure 1 is a perspective view of a combined place card and flower holder, showing my new design.

I claim:

The ornamental design for a combined place card and flower holder, as shown.

EDNA L. SANDERS.
